UNITED STATES PATENT OFFICE

FRANK BERN, OF CLEVELAND, OHIO

PHOTOGRAPHIC PRINTING DEVICE

Application filed January 16, 1932. Serial No. 586,985.

This invention relates to improvements in photographic printing devices for use in making, by projection, bordered photographs, such as enlargements.

The photographic printing device of the present application is in many respects an improvement over the photographic printing devices of my prior Patents No. 1,817,606 and No. 1,818,528, although the principles underlying the present device are the same as those underlying the devices of said prior patents.

The features of the present photographic printing device which enable more varied and more beautiful border effects to be produced, by simple projection, will appear from the following description of the present invention, reference being had to the accompanying drawings in which

Fig. 1 is a top plan view of the present device with the image mask and the inner border mask means in masking position; Fig. 2 is a similar view but with the image mask removed; Fig. 3 is a cross-sectional view of the present device, the view being taken on the line 3-3, Fig. 1; Fig. 4 is a cross-sectional view of a part of said device, the view being taken on the line 4-4, Fig. 1; Fig. 5 is a top plan view of the present device with one of the two inner border mask members thereof swung to non-masking position; Fig. 6 is a cross-sectional view of a part of the present device, the view being on the line 6-6, Fig. 8; Fig. 7 is a view similar to Fig. 5 but showing both of the inner border mask members swung to non-masking position; Fig. 8 is a view similar to Fig. 5 but showing, in masking position, two inner border end mask members; Fig. 9 is a fragmentary top plan view of the present device, showing both of the inner border mask members in non-masking position and with one of the inner border end mask members in masking position; Fig. 10 is a top plan view of the inner border design carrying member; and Fig. 11 is a fragmentary top plan view of a representation of a bordered photograph made with the use of the present device.

The photographic printing device here illustrated includes an outer border mask

having an opaque area 1 and a light-transmitting area comprising an image-exposing portion 2 and an inner-border-exposing portion 3. In the preferred embodiment of the invention, the light-transmitting area of this outer border mask is in the form of a single opening, the opaque area of said mask being in one piece and made of any suitable material, such as aluminum.

For masking the inner-border-exposing portion 3 of the light-transmitting area of the outer border mask, during the printing of the image portion of the photograph, suitable inner border mask means is provided. In the device here illustrated, the inner border mask means comprises two mask members 5 and 6, each preferably in one piece and each preferably made of aluminum. The top end of the inner border mask member 5 is hinged at 8 to the upper surface of the top end portion of the opaque area 1 of the outer border mask and the right hand side portion, as viewed in the drawings, of the inner border mask member 6 is hinged at 9 to the upper surface of the right hand side portion of said opaque area of said outer border mask. As clearly shown in the drawings, the inner border mask member 5 is adapted, when in masking position relative to the outer border mask, to overlie and therefore mask the inner part of the inner-border-exposing portion 3 of the light-transmitting area of the outer border mask, and the inner border mask member 6 is adapted, when in masking position relative to the outer border mask, to overlie and therefore mask the outer part of the inner-border-exposing portion 3 of the light-transmitting area of the outer border mask. When both of the inner border mask members 5 and 6 are in masking position with respect to the outer border mask, as in Fig. 2, for example, the entire inner-border-exposing portion 3 of the light-transmitting area of the outer border mask is covered or masked, leaving only the image-exposing portion 2 of said light-transmitting area exposed through the central, light-transmitting opening of the inner border mask member 5, this being the position of the parts during the printing of the image portion of the photograph.

For masking the image-exposing portion 2 of the light-transmitting area of the outer border mask, during the printing of the inner border portion of the photograph, a suitable image mask 12 is provided, said mask having its entire area opaque and being a separate removable member, preferably made of aluminum. If desired and as shown, the image mask may be provided on its upper surface with one or more transversely disposed ribs 13, two being here shown, said ribs giving said mask increased strength and rigidity and also enabling it to be more easily and conveniently handled. For a purpose which will later appear, the marginal top edges of the image mask are bevelled, as at 15. As clearly shown in Fig. 1, the image mask 12 is slightly smaller than the image-exposing portion 2 of the light-transmitting area of the outer border mask. Therefore, when the image mask is in masking position, as in Fig. 1, for example, there is exposed at 18 a continuously extending, small amount of the marginal part of the image-exposing portion 2 of said outer border mask. Inasmuch as the light-transmitting opening of the inner border mask member 5 coincides with the image-exposing portion 2 of the outer border mask, when said inner border mask member 30 is in masking position relative to said outer border mask, (said image-exposing portion 2, as a matter of fact, being defined or determined by said light-transmitting opening of said inner border mask member 5), it follows that the exposed marginal part 18 of said image-exposing portion of said outer border mask lies between the outer bevelled edge 15 of the image mask and the inner edge 20 of the inner border mask member 5. The purpose of exposing the marginal part 18 of the image-exposing portion 2 of the light-transmitting area of the outer border mask is to provide in the photograph a narrow border at the edge of the image portion of the photograph, as will later more fully appear.

To properly position or center the image mask 12 relative to the image-exposing portion 2 of the light-transmitting area of the outer border mask, so as to have, of uniform width throughout, the exposed marginal part 18 of said image-exposing portion, suitable positioning or centering means is provided for said image mask. The positioning or centering means here shown comprises a cross bar 25, of aluminum, for example, and adapted for simple and quick connection to and disconnection from the image mask 12 and the inner border mask member 5. For this purpose, said cross bar is provided in its middle portion with one or more depending position-determining pins 26 adapted to enter suitable openings 27 in bosses 28 of the image mask 12 and also provided in its two end portions with like pins 29 adapted to enter suitable openings 30 in the inner border mask

member 5. By the use of this cross bar, the image mask can be easily and quickly centered or properly positioned relative to the image-exposing portion 2 of the light-transmitting area of the outer border mask, thereby insuring that the exposed marginal part 18 of said image-exposing portion will be of uniform width throughout. After thus centering said image mask, the cross bar 25 is removed, which is, of course, quite easy to do. 70 75

In order to produce, by simple projection, in the inner border portion of the photograph, some pleasing inner border design, a suitable design-carrying member is utilized, said member being preferably one of a series 80 of such members, so that a photograph can be given any selected inner border design. 85

The design-carrying members of the present device are preferably simple one-piece members of some suitable sheet material, such as brass, copper, celluloid, glass and the like. The inner border designs of said members are of various forms and are made by providing in said members suitable light-transmitting portions, which portions may be 90 in the form of openings made by any suitable means. Each of the present design-carrying members includes an opaque area 35, a light-transmitting area 36 and an inner border design area 37. The opaque area 35 95 of each design-carrying member corresponds to the opaque area 1 of the outer border mask, and when said design-carrying member is secured to said outer border mask, as shown in Fig. 3, for example, the opaque area of 100 said design-carrying member coincides with said opaque area of said outer border mask. The light-transmitting area 36 of each design-carrying member is preferably in the form of a single opening and corresponds to 105 the image-exposing portion 2 of the light-transmitting area of the outer border mask. When said design-carrying member is secured to said mask, as shown in Fig. 3, for example, the light-transmitting opening 36 110 of said design-carrying member coincides with said image-exposing portion 2 of said outer border mask. The design area 37 of 115 each design-carrying member is provided with suitable light-transmitting design portions, the shapes of which are reproduced in the inner border portion of the photograph and constitute the inner border design thereof. As before mentioned, these light-transmitting design portions may be and are 120 here shown in the form of simple openings, being denoted in the design-carrying member 40 of Fig. 10 by the reference character 42. 125

In the design-carrying member 45 illustrated in Figs. 3 to 9 inclusive, the design area 37 thereof is provided with light-transmitting design portions in the form of two generally rectangular slots, there being an inner slot 47 and an outer slot 48, said slots being connected at suitable intervals by webs 50. 130

In use, the selected design-carrying member is removably secured to the bottom surface of the opaque area 1 of the outer border mask, the securement being effected by any suitable means, such as screws 52 extending through suitable openings 53 in the corners of the design-carrying member and entering suitable threaded openings in the corners of the opaque area 1 of the outer border mask. Inasmuch as each design-carrying member is of the same size as the outer border mask, proper securement of a design-carrying member to the outer border mask is quite simple to attain.

Due to the fact that the present device has two inner border mask members 5 and 6, one of which is for the outer part of the inner border portion of the photograph and the other of which is for the inner border part of the inner border portion of the photograph, either the entire inner border design of the selected design-carrying member or the inner part only thereof can be reproduced in the inner border portion of the photograph.

If it is desired to reproduce in the photograph the entire inner border design of the selected design-carrying member, then both the inner border mask members 5 and 6 are swung to non-masking position, as in Fig. 7, for example. If, however, it is desired to reproduce in the photograph only the inner part of the inner border design of the selected design-carrying member, such as the inner, generally rectangular line 47 of the design-carrying member 45, then the inner border mask member 5 is swung to non-masking position, as in Fig. 5, leaving in masking position the other inner border mask member 6. In most instances, however, it will probably be desired to reproduce in the photograph the entire inner border design of the selected design-carrying member, rather than only the inner part of said design.

If desired, the use of a design-carrying member may be entirely dispensed with, and the inner border of the photograph produced by the use of the two inner border mask members alone. For example, a very attractive inner border effect can be produced by first moving to non-masking position the inner border mask member 5 and thereafter also moving to non-masking position the other inner border mask member 6. This will cause the inner part of the inner border portion of the sensitized sheet which is to receive the bordered photograph to be exposed twice to the light of the camera and the outer part of said inner border portion to be exposed once, thereby making the inner part of said inner border portion of the photograph darker than the outer part thereof.

It is, of course, to be understood that during the entire photographic printing operation, the present device overlies the sensitized sheet which is to receive the bordered

photograph. Figs. 3, 4 and 6 best show these parts in such relation, the sensitized sheet being denoted by the reference numeral 60 and lying on a table or other suitable support 61. Due to the fact that the sensitized sheet 60 and the outer border mask are of the same size, it is a simple matter to obtain registration of these parts, as will be readily understood.

In Fig. 11 is shown a representation of a bordered photograph made with the use of the present device. In this view 65 represents the outer border portion of the photograph and 67 represents the image portion thereof. Between these two portions is the inner border portion 68 of the photograph. Just within the image portion of the photograph is the rectangularly shaped, narrow border line 18, produced by having the image mask 12 slightly smaller in size than the image-exposing portion 2 of the light-transmitting area of the outer border mask. If desired a photograph can have for its entire inner border effect this line 18, such a result being accomplished by simply leaving in masking position both of the inner border mask members 5 and 6. Or, if desired, a photograph can have this border line 18 augmented by two plain inner border parts, namely, an inner part 70 and an outer part 71. The inner part 70 will be the part that is selectively masked or exposed by the inner border mask member 5 and the outer part 71 will be the part that is selectively masked or exposed by the inner border mask member 6. As before mentioned, a very attractive inner border effect can be produced by giving the inner part 70 of the inner border portion of the photograph two exposures and giving the outer part 71 thereof but one, an effect accomplished by first moving to non-masking position the inner border mask member 5 and thereafter also moving to non-masking position the other inner border mask member 6. A photograph produced in this way will have the inner border line 18, a plain more or less dark border inner part 70 and a plain, lighter colored border outer part 71. In making such a photograph, the use of a design-carrying member is unnecessary, as will be readily understood.

In making the photograph represented in Fig. 11, however, a design-carrying member is used, the one chosen being the one shown in Figs. 3 to 9 inclusive and being represented by the reference numeral 45. As before mentioned, the design of this member comprises two generally rectangular lines, there being an inner line 47 and an outer line 48, said lines being interconnected at suitable intervals by lines 50. If desired, this entire design can be produced at one time in the inner border portion of the photograph by moving to non-masking position both of the inner border mask members 5 and 6. In such

a case, all parts of all lines of the design will be of the same color in the photograph. If desired, however, and as shown in the photograph of Fig. 11, the inner line 47 is darker than the outer line 48, an effect accomplished by giving the inner part of said inner border design two exposures and giving the outer part thereof one exposure. It will thus be seen that by having the inner border mask means in the form of an inner member 5 and an outer member 6, with said members individually movable into and out of masking position, many varied border effects can be obtained, either with or without the use of a design-carrying member.

Some particularly attractive inner border effects can be obtained by having the edges of the inner border parts 70 and 71 of the photograph, as well as the edges of the border lines, etc., produced by the use of a design-carrying member, more or less indistinct or undefined, rather than sharp. Such effects can be obtained by spacing, during the photographic printing operation, the present device, with the exception of the image mask 12 thereof, above the sensitized sheet which is to receive the bordered photograph. This permits the light of the enlarging camera to get below the edges of the light-transmitting portions of the present device, with more or less diffusion of said light at said edges.

The means here shown for so spacing the present device above the sensitized sheet during the photographic printing operation, comprises a simple rectangular frame 78, of aluminum or the like, and having a width less than that of the opaque area of the outer border mask. In use, this frame is removably secured, by screws 80 or the like, to the bottom of the opaque area of the outer border mask, the design-carrying member, if there is one, being secured between said frame and said opaque area, all as shown in Fig. 3.

In order to prevent the production in the photograph of white spots adjacent the border line 18, the result of a lack of proper exposure of said spots, the top marginal edge portion 15 of the image mask 12 is bevelled, as before mentioned, and also, the inner marginal portion 75 of the inner border mask member 5 is bent downwardly and inwardly, as best shown in Fig. 3. By so inclining these marginal edge portions 15 and 75 of the image mask 12 and the inner border mask member 5 respectively, the light of the enlarging camera falling on these parts is reflected upwardly, rather than onto the sensitized sheet which is to receive the bordered photograph. This feature of the present device is quite important, as it prevents the formation of shadows and white spots in the photograph even though the enlarging camera is not located directly over the center of the image mask during the photographic printing operation.

In order to obtain with the use of the present device further varied inner bordered effects, two inner border mask end members are provided, said members being shown in Figs. 6, 8 and 9. These mask end members are adapted to mask either the entire end parts of the inner border-exposing portion 2 of the outer border mask, as in Fig. 9, or the inner portions only of said end parts, as in Fig. 8. If the entire end parts of the inner border-exposing portion 2 of the outer border mask are to be masked, as in Fig. 9, then both of the inner border mask members 5 and 6 are moved to non-masking position, as shown. If, however, only the inner portions of said end parts are to be masked, as in Fig. 8, then only the inner border mask member 5 is moved to non-masking position, as shown.

In the present embodiment of the invention, these two mask end members are of identical construction, each being preferably a simple one-piece member of aluminum or other suitable material. Each comprises a top supporting portion 89 and a forwardly and downwardly inclined masking portion 90 having diagonally cut end edges 91. In use of these mask end members, the top portions 89 thereof rest upon the top surfaces of either the end portions of the inner border mask member 5 or the end portions of the opaque area 1 of the outer border mask. The bottom edges of the masking portions 90 of said mask end members rest upon either the sensitized sheet 60 which is to receive the bordered photograph or on the design-carrying member, if one is being used. In order to insure proper positioning of said mask end members relative to the end parts of the inner border-exposing portion 2 of the outer border mask, the top portions 89 of said mask end members are provided with suitable depending, position-determining pins 95 which are adapted to enter suitable openings 96 in the end portions of the inner border mask member 6 or suitable openings 97 in the opaque area 1 of the outer border mask. As before mentioned, the masking portions 90 of said mask end members are suitably inclined, so that the light of the enlarging camera will not be reflected thereby onto the sensitized photograph-receiving sheet 60.

As stated above, the two inner border mask members 5 and 6 are hinged to the opaque area 1 of the outer border mask, so that said inner border mask members always assume their proper masking positions relative to the outer border mask. However, wear of their hinges may occur, with consequent liability of improper positioning of said inner border mask members and to prevent such improper positioning, the free end portion of the inner border mask member 5 is provided with a depending, position-determining pin 99 adapted to enter a suitable opening 100 in the lower end portion of the inner border mask member 6.

Likewise, the free side portion of the inner border mask member 6 is provided with a depending, position-determining pin 101 adapted to enter a suitable opening 102 in the left hand side portion, as viewed in the drawings, of the opaque area 1 of the outer border mask, all as clearly shown in the drawings and as will be readily understood. For more conveniently moving the inner border mask members 5 and 6, each thereof is preferably provided at its free end with a suitable handle or knob 104, as shown.

What I claim is:

1. A photographic printing device for making bordered photographs by projection, said device comprising an outer border mask; inner border mask means; and an image mask; said outer border mask having an opaque area and a light-transmitting area, said light-transmitting area comprising an image-exposing portion and an inner border-exposing portion, said outer border mask being adapted, during the entire photographic printing operation, to have its opaque area overlie and therefore mask the outer border portion of the sensitized sheet which is to receive the bordered photograph and to have its image-exposing portion and its inner border-exposing portion respectively overlie the image portion and the inner border portion of said sensitized sheet; said inner border mask means comprising two mask members individually movable into and out of masking relation relative to said outer border mask, one of said inner border mask members being adapted to overlie and therefore mask a part of the inner border-exposing portion of the outer border mask and the other of said inner border mask members being adapted to overlie and therefore mask the remaining part of said inner border-exposing portion of said outer border mask, both of said inner border mask members being adapted to be moved to masking position relative to the outer border mask during the printing of the image portion of the photograph; and said image mask having its entire area opaque and being movable into and out of masking relation relative to said outer border mask, said image mask, during the printing of the inner border portion of the photograph, being adapted to overlie and therefore mask the image-exposing portion of the light-transmitting area of the outer border mask.
2. A photographic printing device as set forth in claim 1, characterized in that both of said inner border mask members are hinged to the opaque area of said outer border mask.
3. A photographic printing device as set forth in claim 1, characterized in that one of said inner border mask members is hinged to the upper surface of the top end portion of the opaque area of the outer border mask and the other of said inner border mask members is hinged to the upper surface of one of the

side portions of said opaque area of said outer border mask.

4. A photographic printing device as set forth in claim 1, characterized in that one of said inner border mask members is adapted to mask the inner part of the inner border-exposing portion of the outer border mask and in that the other of said inner border mask members is adapted to mask the outer part of the inner border-exposing portion of the outer border mask.

5. A photographic printing device as set forth in claim 1, characterized in that means is provided for spacing, during the photographic printing operation, the outer border mask and the inner border mask means above the sensitized sheet which is to receive the bordered photograph.

6. A photographic printing device as set forth in claim 1, characterized in that means is provided for spacing, during the photographic printing operation, the outer border mask and the inner border mask means above the sensitized sheet which is to receive the bordered photograph, said means comprising a generally rectangular frame adapted to be secured to the bottom of the opaque area of the outer border mask.

7. A photographic printing device as set forth in claim 1, characterized in that said image mask is slightly smaller than the image-exposing portion of the light-transmitting area of the outer border mask.

8. A photographic printing device as set forth in claim 1, characterized in that said image mask is slightly smaller than the image-exposing portion of the light-transmitting area of the outer border mask and characterized further in that means is provided for properly positioning said image mask relative to said image-exposing portion of said outer border mask.

9. A photographic printing device as set forth in claim 1, characterized in that said image mask is slightly smaller than the image-exposing portion of the light-transmitting area of the outer border mask and characterized further in that means is provided for properly positioning said image mask relative to said image-exposing portion of said outer border mask, said positioning means comprising a cross bar adapted to be removably secured to said image mask and to said inner border mask means.

10. A photographic printing device as set forth in claim 1, characterized in that said image mask is slightly smaller than the image-exposing portion of the light-transmitting area of the outer border mask and characterized further in that means is provided for properly positioning said image mask relative to said image-exposing portion of said outer border mask, said positioning means comprising a cross bar provided with depending, position-determining pins

adapted to enter openings in said image mask and said inner border mask means, whereby said cross bar can be removably secured to said image mask and said inner border mask means, and the proper positioning of said image mask thereby effected.

11. A photographic printing device as set forth in claim 1, characterized in that one of said inner border mask members is hinged to the opaque area of said outer border mask and characterized further in that the free end portion of said hinged inner border mask member is provided with a depending, position-determining pin adapted to enter an opening in the opaque area of said outer border mask, whereby said inner border mask member will always assume the same masking position relative to said outer border mask.

12. A photographic printing device as set forth in claim 1, characterized in that the marginal top portion of said image mask is bevelled.

13. A photographic printing device as set forth in claim 1, characterized in that one of said inner border mask members has a light-transmitting opening which coincides, when said member is in masking position relative to said outer border mask, with the image-exposing portion of the light-transmitting area of said outer border mask, said inner border mask member, around its light-transmitting opening, being inclined downwardly and inwardly, and characterized further in that the marginal top portion of said image mask is inclined downwardly and outwardly.

14. A photographic printing device as set forth in claim 1, characterized in that a mask end member is provided for each end part of the inner border-exposing portion of the light-transmitting area of the outer border mask.

15. A photographic printing device as set forth in claim 1, characterized in that a mask end member is provided for each end part of the inner border-exposing portion of the light-transmitting area of the outer border mask, each of said mask end members having diagonally cut end edges.

16. A photographic printing device as set forth in claim 1, characterized in that a mask end member is provided for each end part of the inner border-exposing portion of the light-transmitting area of the outer border mask, each of said mask end members having a supporting portion adapted for removable securement to either the opaque area of the outer border mask or to one of the inner border mask members.

17. A photographic printing device as set forth in claim 1, characterized in that a mask end member is provided for each end part of the inner border-exposing portion of the light-transmitting area of the outer border mask, each of said mask end members having a supporting portion and a masking portion,

the masking portion of each mask end member, when said member is in masking position, being inclined downwardly and inwardly relative to the image-exposing portion of said outer border mask.

18. A photographic printing device as set forth in claim 1, characterized in that a mask end member is provided for each end part of the inner border-exposing portion of the light-transmitting area of the outer border mask, each of said mask end members having a supporting portion and a masking portion, the supporting portion of each mask end member being provided with depending, position-determining pins adapted to enter openings either in the opaque area of the outer border mask or in one of the inner border mask members.

19. A photographic printing device as set forth in claim 1, characterized in that a design-carrying member is adapted to be removably secured to the opaque area of the outer border mask in such position that the design of said member lies below the inner border-exposing portion of said outer border mask, the design of said member being made up of light-transmitting portions.

20. A photographic printing device as set forth in claim 1, characterized in that a design-carrying member is adapted to be removably secured to the opaque area of the outer border mask in such position that the design of said member, made up of light-transmitting portions, lies below the inner border-exposing portion of said outer border mask, said design-carrying member being in one piece and also having a light-transmitting image-exposing portion adapted, when said design-carrying member is secured to said outer border mask, to coincide with the image-exposing portion of said outer border mask.

In testimony whereof I hereby affix my signature.
